UNITED STATES PATENT OFFICE.

JOHN PRIMROSE, OF NEW YORK, N. Y., ASSIGNOR TO POWER SPECIALTY COMPANY, A CORPORATION OF NEW YORK.

SUPERHEATER-HEADER.

1,129,122.

Specification of Letters Patent. Patented Feb. 23, 1915.

Application filed May 26, 1914. Serial No. 840,980.

To all whom it may concern:

Be it known that I, JOHN PRIMROSE, a subject of the King of Great Britain, residing at New York, in the county and State of New York, have invented certain new and useful Improvements in Superheater-Headers, of which the following is a full, clear, and exact description.

The invention which constitutes the subject-matter of this application relates to an improvement in superheaters, and has to do particularly with the type of superheater in which the individual units or elements are projected rearwardly from the smoke-box, in which the superheater is located, into the fire tubes of a locomotive or other boiler.

The invention resides more particularly in the form of header used, one of the more important features consisting in the provision of an enlargement at the central portions of the saturated and superheated steam chambers, so that the dry-pipe may be removed from the locomotive through said enlargement while using the chambers of medium size and without disturbing the position of the superheater.

In the drawings, Figure 1 is a longitudinal section of my device on the line *a—b* of Fig. 2, illustrating the manner in which the superheater is connected to the tube sheet of the boiler, and its relation to the dry-pipe and fire-tubes of said boiler. Fig. 2 is a front view of the superheater parts thereof being in section. Fig. 3 is a top plan view of the header, with the enlargement shown in central longitudinal section. Fig. 4 is a section of one of the header chambers taken on the line *e—f* of Fig. 3. Fig. 5 is a view in perspective showing the various parts of the header before they have been assembled and welded.

Referring to the drawing in detail, the reference numeral 10 designates the forward portion of a locomotive or stationary boiler, provided with the usual fire tubes 11, smoke box 12, tube sheet 13, and dry pipe 14. The superheater comprises a saturated steam chamber 15, the superheated steam chamber 16, the enlargement 17 constituting a part of the header and to which the chambers

are independently welded or otherwise secured, and the superheating element or units 33, which project rearwardly into the fire tubes 11 and the inlet and outlet ends of which are expanded respectively into the inlet and outlet chambers 15 and 16. 55

The saturated and superheated steam compartments 18 and 19 are formed by welding or the otherwise securing together of the chambers 15 and 16 to the cylindrical enlargement 17. The manner in which these parts are constructed is clearly illustrated in Figs. 3, 4 and 5. The enlargement 17 is provided with two openings *a*, *b*, through the side thereof which preferably correspond in shape and size to the shape and size of the openings *a'*, *b'* in the chambers 15 and 16. In the embodiment shown these openings are both substantially rectangular and semicircular in shape. 65

The cylindrical enlargement is provided with continuous annular flanges 20, 21, for direct connection with the dry-pipe, and to provide a securing means for the closure 22. The enlargement is also provided with an internal annular flange 23, and this flange, in conjunction with the closure 24, divides the enlargement into two separate chambers 25, 26, which constitute parts of the compartments 18 and 19, respectively. The header therefore comprises an enlargement provided with a partition dividing the same into saturated and superheated steam chambers, in combination with saturated and superheated steam chambers welded or otherwise secured to said enlargement, the last mentioned saturated steam chambers in conjunction with said saturated steam chamber of said enlargement constituting the saturated steam compartment of the superheater, and the last mentioned steam chamber in conjunction with the superheated steam chamber of said enlargement constituting the superheated steam compartment of the superheater. 85

From the construction above described, it will be seen that I have devised a superheater in which the chambers are of normal size, each independently welded or otherwise connected to the enlargement, and in 100

which provision is made for withdrawing the dry-pipe through the latter for replacement or repairs. It is only necessary to remove the closures 22 and 24 in order to do this, which affords ready access to the said dry-pipe. Consequently I obtain not only all the advantages secured by the drum, but others in addition, as will be apparent. It is of course understood that there is quite a difference in temperature between the saturated steam in the inlet chamber and the superheated steam in the outlet chamber. The feature therefore of having the chambers independently connected allows each to expand and freely accommodate itself to its own temperature. Of course provision is made in the way of hand-holes 27 for affording access to the ends of the superheating units, whereby the same may be expanded into place or removed from the headers, as desired.

Another feature of this invention consists in providing supports 28 for the superheating units, which take up all strain upon the superheaters whenever, for any reason, the locomotive comes to a sudden stop, or is otherwise jarred. These supports 28 are mounted upon suitable brackets 29, located upon the interior wall of the smoke-box, and are further provided with screw-threaded bolts, welded or otherwise secured thereto, and projecting in a longitudinal direction with respect to the smoke-box. These bolts, or rather screw-threaded projections, are adapted to enter perforated lugs welded or otherwise secured to the return bonds of the superheater units, and it will be seen that a rigid connection is secured whenever the nuts 31 are in place. It is necessary to have the bolts projecting from the supports 28 longitudinally arranged, for convenience in placing the nuts 31 thereon.

The headers may be supported either by the tube sheet or by the brackets 32, or by both, as desired.

What I claim is:

1. A superheater comprising saturated and superheated steam chambers, a dry-pipe, and an enlargement to which said chambers are welded or otherwise secured and through which the dry pipe of the locomotive may be passed, and superheating units expanded into said chambers.

2. A superheater comprising a substantially cylindrical or drum-shaped portion to which the dry-pipe is connected and through which it may be removed, said portion having a partition therein dividing the same into separate chambers in combination with chambers welded to said drum-shaped portion and in direct communication with the chambers of the latter, the said chambers constituting the saturated and superheated steam compartments of said superheater,

and superheater units expanded into said chambers.

3. A superheater comprising an enlarged portion to which the dry-pipe is connected and through which it may be removed, in combination with saturated and superheated steam chambers welded or otherwise secured to said portion independently of each other whereby each accommodates itself to its own temperature, and superheater units expanded into said chambers.

4. A superheater comprising a substantially cylindrical or drum shaped enlargement to which the dry-pipe is connected and through which it is adapted to be removed, said enlargement having a partition therein dividing the same into separate chambers, in combination with saturated and superheated steam chambers welded or otherwise secured to said enlargement and in direct communication with the chambers of the latter, said saturated and superheated steam chambers connected to said enlargement independently of each other whereby each accommodates itself to its own temperature, and superheater units expanded into said chambers.

5. In combination with a boiler, of a superheater, comprising a header located in the smoke-box, and superheater units having perforated lugs and projecting rearwardly into a plurality of fire tubes, the ends of said units being expanded into said header, in combination with means for rigidly anchoring said units, comprising cross bars secured to the interior of the smoke-box and provided with projecting bolts thereon, and means for securing the said bolts to the said lugs.

6. In combination with a boiler, a superheater comprising a transverse or extension header located in and supported by the walls of the smoke box, and superheater units having perforated lugs and projecting rearwardly into a plurality of fire tubes, the ends of said units being expanded into said header, in combination with means for rigidly anchoring said units comprising a plurality of cross-bars secured to the interior of said smoke box and each provided with a plurality of bolts arranged substantially parallel to the longitudinal axis of said boiler, and means for securing said bolts to said lugs.

7. A header for a superheater comprising an enlargement to which the dry-pipe is adapted to be connected and through which it may be removed, said enlargement provided with a partition dividing the same into saturated and superheated steam chambers, in combination with saturated and superheated steam chambers welded or otherwise secured to said enlargement, the last mentioned saturated steam chamber in conjunction with said saturated steam cham-

ber of said enlargement constituting the saturated steam compartment of the superheater, and the last mentioned superheated steam chamber in conjunction with the superheated steam chamber of said enlargement constituting the superheated steam compartment of the superheater.

In testimony whereof I affix my signature in the presence of two subscribing witnesses.

JOHN PRIMROSE.

DISCLAIMER.

1,129,122.—*John Primrose*, New York, N. Y. SUPERHEATER-HEADER. Patent dated February 23, 1915. Disclaimer filed April 7, 1916, by the assignee, *Power Specialty Company, New York, N. Y.*

Enters this disclaimer—

"To that part of the description on page 2 of the patent which is lines 22 to 43, both inclusive, and to claims 5 and 6, which are in the following words, to wit:

"Another feature of this invention consists in providing supports 28 for the superheating units, which take up all strain upon the superheaters whenever, for any reason, the locomotive comes to a sudden stop, or is otherwise jarred. These supports 28 are mounted upon suitable brackets 29, located upon the interior wall of the smoke-box, and are further provided with screw-threaded bolts, welded or otherwise secured thereto, and projecting in a longitudinal direction with respect to the smoke-box. These bolts, or rather screw-threaded projections, are adapted to enter perforated lugs welded or otherwise secured to the return bends of the superheater units, and it will be seen that a rigid connection is secured whenever the nuts 31 are in place. It is necessary to have the bolts projecting from the supports 28 longitudinally arranged, for convenience in placing the nuts 31 thereon.

"5. In combination with a boiler, of a superheater, comprising a header located in the smoke-box, and superheater units having perforated lugs and projecting rearwardly into a plurality of fire tubes, the ends of said units being expanded into said header, in combination with means for rigidly anchoring said units, comprising cross bars secured to the interior of the smoke-box and provided with projecting bolts thereon, and means for securing the said bolts to the said lugs.

"6. In combination with a boiler, a superheater comprising a transverse or extension header located in and supported by the walls of the smoke box, and superheater units having perforated lugs and projecting rearwardly into a plurality of fire tubes, the ends of said units being expanded into said header, in combination with means for rigidly anchoring said units comprising a plurality of cross-bars secured to the interior of said smoke box and each provided with a plurality of bolts arranged substantially parallel to the longitudinal axis of said boiler, and means for securing said bolts to said lugs."
